UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed July 15, 1927. Serial No. 205,899.

My invention relates to engine starting apparatus for the starting of internal combustion engines, more particularly but not necessarily automobile engines, and the object 5 thereof is to provide a simple, efficient, and reliable apparatus characterized by a drive of the manual shift type composed of a driving member or pinion adapted to engage a member of the engine to be started, such 10 as a flywheel, a control member or nut threaded upon a longitudinally movable sleeve and having a friction clutch interposed between the driving member and control member, and further characterized by the provision of 15 novel means for shifting the drive proper longitudinally to bring the driving member into engagement with the engine member and also means which is extraneous to the drive proper and which is actuated by said shifting 20 means for slightly rotating such drive, more particularly the driving member in the event of abutting of the driving member and engine member.

In the drawings, Figure 1 is an elevation 25 partly in section of an engine starting apparatus embodying my invention;

Fig. 2 a section of the drive proper and shifting means;

Fig. 3 an end elevation of the drive proper; 30 Fig. 4 a section on the line 4—4 of Fig. 2;

Fig. 5 an end elevation of one of the shifter sleeves;

Fig. 6 a side elevation of such shifter sleeve;

Fig. 7 a section of the control member or nut taken on the line 7—7 of Fig. 8;

Fig. 8 an end view of such nut;

Fig. 9 an elevation of the screw shaft or sleeve alone;

Fig. 10 an end elevation thereof; and

Fig. 11 an end elevation of the nut and its disk.

Referring to the particular embodiment 45 of my invention as herein shown and selected for the purposes of a clear and definite description, the prime mover is in the form of an electric motor 1 and as the particular construction herein shown is the so-called direct drive, the rotatable driving shaft 2 for the drive comprises the extended armature shaft of the motor. A casing or bracket 3 extends from the frame of the motor and at its outer end, the same is provided with a bearing 4 for the outer end of such shaft 2.

This casing also forms a support for a shifting lever 5 which is pivoted to such casing or bracket at 6 and which extends into the casing with its lower end 7 in a position to engage the shifting means hereinafter described. This lever 5 is provided with an angular arm 8 which in its oscillating travel in a clockwise direction is adapted to contact and operate the button 9 of a switch not otherwise shown of the electric motor for supplying such motor with current and cutting it off therefrom. This lever 5 is adapted to be manually or pedally operated by the operator through suitable linkage or operating connections which are of the usual character and therefore not required to be shown, except that one of the rods 10 thereof is illustrated in Fig. 1. The term "manually" will be hereinafter employed generically to include pedal operation, as well as manual operation. This casing 3 is secured to the frame 75 of the electric motor in a suitable manner as by means of the screws 11.

The drive proper is an assembly together with the shifting means, and the same is adapted to be slipped upon the driving shaft 80 2 before the casing 3 is applied and secured to the motor, and such drive is so mounted as to slide upon such shaft and to be driven thereby.

The drive proper comprises a sleeve 12 85 which is mounted upon the shaft 2 for longitudinal movement thereof and rotary movement therewith, such result being accomplished in the present instance by means of the splines 13 on the shaft 2 and the corresponding grooves 14 in the bore of the sleeve 12. This sleeve is provided at its outer or left-hand end with suitable stop means which is here in the form of a nut 15 screwing upon the end thereof and secured firmly thereto. The sleeve is provided with a screw threaded portion 16 composed of short lead threads and at its inner or right-hand end it has an enlarged shell extension 17 provided with opposite longitudinal slots 17a.

The driving member is here in the form of a pinion 18 which is normally in substantial contact with the stop nut 15 and is mounted upon the sleeve 12, preferably through the medium of a bushing 19. This pinion is 105 adapted when shifted longitudinally to the left to engage the engine member which is here in the form of a flywheel 20 having

peripheral teeth 21 for engagement with the pinion 18.

The control member is in the form of a nut 22 which is threaded upon the screw threaded portion 16 of the sleeve 12 and the same is provided at its left-hand end with a cup-shaped disk 23. These two parts are made separate, but are suitably and firmly secured together. A light torsion spring 24 encircles the nut 22 and the sleeve 12 and the same is fastened at its opposite ends to such nut and sleeve respectively.

Between the pinion 18 and nut 22 and operatively connected with both of them, there is positioned a friction clutch which is composed of two sets of plates 25 and 26, the former set being splined to a hub extension of the pinion and the other set to the longitudinally extending portion of the disk 23 of the nut. A ring 27 is preferably interposed between the disk 23 and the first of the clutch plates 26. Suitable means are provided for retaining the clutch assembly upon the pinion, and as shown, a spring ring or wire 28 is employed, the same being located at the base of two of the outermost plates 26 at the right-hand end of the clutch plates and engaging an inner groove in the hub extension of the pinion. A shell 29 encloses the clutch plates and the same is held fastened to the disk 23 in a suitable manner as by means of a spring ring or wire 30. Inasmuch as all the clutch plates, except the plate 25 adjacent the pinion teeth and the member 23 are held together by this shell 29, the entire clutch assembly will be retained upon the pinion no matter where the ring 28 may be located longitudinally, so long as it is behind the second clutch plate, and, as shown, it is behind the fourth inner clutch plate 25.

Referring to the means for shifting the drive longitudinally and also partially rotating the same, the same comprise in the present instance two cooperating sleeves, such as the shifter sleeve 31 and an intermediate sleeve 32. The sleeve 31 is provided with parallel flanges 33 between which the inner end 7 of the shifting lever 5 operates and by which it is operatively connected with the sleeve 31. This latter sleeve has a pin and inclined slot connection with the sleeve 32, the pins 34 being located in the sleeve 31 and the slots 35 being located in the sleeve 32, whereby the sleeve 32 can partake of both a longitudinal and an enforced rotary movement as herein-after explained. These pins 34 also pass through the longitudinal slots 17^a in the extension 17 of the screw sleeve, upon whose periphery the sleeve 32 is mounted to slide.

A spring retainer in the form of a shell 36 is connected with the left-hand end of the sleeve 32 and a thimble 37 is held by the pins 34 and 34^a in a position at the right-hand end of such sleeve 32. A compression spring 38 is interposed between this shell 36 and thimble

37 whereby the sleeves 31 and 32 are held in a normal relative position which is the extended position shown in Figs. 1 and 2.

The sleeve 32 is capable of rotary movement, and it is one of the features of this invention to transmit such rotary movement to the nut 22 and thereby to the entire drive including the pinion 18 so as to relieve the latter from a condition of abutting against the end of the flywheel teeth and permit of the registry of such teeth and the consequent meshing of the pinion and flywheel. As herein shown, the sleeve 32 is provided at its left-hand end with an inwardly directed flange 39 on whose outer face there is provided a ring of projections or teeth 40 which are adapted to engage a similar ring of projections or teeth 41 on the adjacent or right-hand end of the nut 22, whereby any partial rotation of the sleeve 32 is transmitted to the nut 22 and to the parts cooperating therewith including the pinion 18.

Describing a cycle of operation of the apparatus and beginning with their parts in their normal position as shown in Figs. 1 and 2, when it is desired to crank and start the engine, the operator oscillates the lever 5 in a clockwise direction thereby shifting the sleeves 31 and 32, and consequently the entire drive assembly to the left and bringing the pinion 18 into mesh with the flywheel. When full or substantially full mesh of the pinion is obtained, the switch is operated by the lever 5 and the motor is energized whereupon the shaft 2 will be rotated and the torque will be transmitted therefrom by the drive to the flywheel through the sleeve 12, nut 22, friction clutch and pinion.

In the event that the pinion teeth should abut the flywheel teeth end to end, thereby arresting the longitudinal movement of the drive, the longitudinal movement of the shifter sleeve 31 will continue because of the provision of the yielding lost drive movement through the spring 38 and as the sleeve 31 is connected with the sleeve 32 through the pin and inclined slot connection described, and as the screw sleeve 12 is now prevented from rotation by the engagement of the pins 34 and the longitudinal slots 17^a in such screw sleeve, the sleeve 32 will not only be advanced longitudinally so as to bring the teeth 40 and 41 into engagement, but the same will thereupon be slightly rotated with the result that the nut 22 will be rotated by such extraneous means and likewise the pinion 18 will be rotated to an extent sufficient to break the abutting condition and bring about register between the pinion teeth and flywheel teeth whereupon the spring 38 which had been compressed during this state of the operation will force the entire drive assembly forward so that the pinion is in mesh with the flywheel gear. This result is accomplished by such registering means as an incident to

the operation of the means for shifting the drive longitudinally along the driving shaft 2.

When the engine starts on its own power, 5 the operator should release his pressure on the lever 5, whereupon these shifting connections through the medium of a spring not shown will retract the entire drive assembly including the shifter means combined therewith and return them to the normal 10 position shown in Fig. 1. If the operator should fail or delay to release such pressure on the operating connections, no harm will be done to the drive or to the motor by the rapid 15 or excess rotation of the pinion 18 by the engine, inasmuch as such excess rotation will cause the nut 22 to back off slightly and relieve the clutching pressure between the clutch plates so that the pinion will rotate 20 freely and without transmitting any of the torque from the engine.

I claim:

1. An engine starter including a rotatable drive shaft, and a drive mounted thereon and 25 driven thereby including a sleeve mounted on the shaft for longitudinal movement thereof and rotary movement therewith, a driving member carried by said sleeve and adapted to be shifted longitudinally to engage a member 30 of the engine to be started, a control member mounted on the sleeve for longitudinal movement thereof and rotary movement therewith, a torque transmitting connection between the driving member and the 35 control member, means for longitudinally shifting said drive, and means operating as an incident to the operation of the shifting means for slightly rotating one of said members in the event that the driving member 40 should abut and not engage the engine member.

2. An engine starter including a rotatable drive shaft, and a drive mounted thereon and driven thereby including a sleeve mounted 45 on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection between the driving member and the 50 control member, means for slightly rotating, as an incident to the longitudinal movement of the drive, one of said members in the event that the driving member should abut and not engage the engine member, and means for holding the sleeve from rotation 55 during such rotation of one of said members.

3. An engine starter including a rotatable drive shaft, and a drive mounted thereon and driven thereby including a sleeve mounted 60 on the shaft for longitudinal movement thereof and rotary movement therewith, a torque transmitting connection interposed between the driving

driving member carried by said sleeve and adapted to be shifted longitudinally to engage a member of the engine to be started, a control member mounted on the sleeve for longitudinal movement thereof and rotary movement therewith, a torque transmitting connection between the driving member and the control member, and means acting on the control member for slightly rotating it and consequently the driving member in the event 70 that the driving member should abut and not engage the engine member.

4. An engine starter including a rotatable drive shaft, and a drive mounted thereon and driven thereby including a sleeve mounted 80 on the shaft for longitudinal movement thereof and rotary movement therewith, a driving member carried by said sleeve and adapted to be shifted longitudinally to engage a member of the engine to be started, a control 85 member mounted on the sleeve for longitudinal movement thereof and rotary movement therewith, a torque transmitting connection between the driving member and the control member, and means comprising a 90 manually operated element operably connected with the sleeve for normally shifting it longitudinally and to partially rotate the driving member should it abut and not engage the engine member.

5. An engine starter including a rotatable drive shaft, and a drive mounted thereon and driven thereby including a sleeve mounted 95 on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection between the driving member and the control member, and means comprising a 100 second sleeve operably connected with the first sleeve, a manually operated element having a pin and inclined slot connection with the second sleeve and mounted for longitudinal movement to longitudinally shift said first sleeve, driving member, control member and clutch and adapted to cause by reason of 110 said pin and slot connection slight rotary movement of said parts mounted on the first sleeve.

6. An engine starter including a rotatable drive shaft, and a drive mounted thereon and driven thereby including a sleeve mounted 115 on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection interposed between the driving 120

125

130

- member and the control member, and means comprising a second sleeve operably connected with the first sleeve, a manually operated third sleeve slidable on said shaft and having pin and inclined slot connection with the second sleeve whereby the latter sleeve is slightly rotated by the stoppage of longitudinal movement of the driving member and the continued longitudinal movement of the 10 third sleeve.
7. An engine starter including a rotatable drive shaft, and a drive mounted thereon and driven thereby including a sleeve mounted on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection interposed between the driving member and the control member, and means comprising a second sleeve operably connected with the first sleeve, a manually operated third sleeve slidable on said shaft and having pin and inclined slot connection with the second sleeve whereby the latter sleeve is slightly rotated by the stoppage of longitudinal movement of the driving member and the continued longitudinal movement of the third sleeve, and yielding means for holding the second and third sleeves in a normal relative position.
8. An engine starter including a rotatable drive shaft, and a drive mounted thereon and driven thereby including a sleeve mounted on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection interposed between the driving member and the control member, and means comprising a second sleeve operably connected with the first sleeve, a manually operated third sleeve slidable on said shaft and having pin and inclined slot connection with the second sleeve whereby the latter sleeve is slightly rotated by the stoppage of longitudinal movement of the driving member and the continued longitudinal movement of the third sleeve, said second and third sleeves being adapted to telescope one into the other, and yielding means for holding such second and third sleeves in a normal relative position longitudinally and rotarily.
9. An engine starter including a rotatable drive shaft, and a drive mounted thereon and driven thereby including a sleeve mounted on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection interposed between the driving member and the control member, and means comprising a second sleeve operably connected with the first sleeve, a manually operated third sleeve slidable on said shaft and having pin and inclined slot connection with the second sleeve whereby the latter sleeve is slightly rotated by the stoppage of longitudinal movement of the driving member and the continued longitudinal movement of the third sleeve, and yielding means for holding such second and third sleeves in a normal relative position longitudinally and rotarily.
10. An engine starter including a rotatable drive shaft, and a drive mounted thereon and driven thereby including a sleeve mounted on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection interposed between the driving member and the control member, and means comprising a second sleeve operably connected with the first sleeve, a manually operated third sleeve slidable on said shaft and having pin and inclined slot connection with the second sleeve whereby the latter sleeve is slightly rotated by the stoppage of longitudinal movement of the driving member and the continued longitudinal movement of the third sleeve, and yielding means for holding such second and third sleeves in a normal relative position longitudinally and rotarily.
11. An engine starter including a rotatable drive shaft, a drive including a sleeve splined on the shaft, a pinion mounted on one end of said sleeve, said sleeve being adapted to be shifted longitudinally to bring the pinion into mesh with a member of the engine to be started, a nut threaded on the sleeve, a torque transmitting connection interposed between the pinion and nut, and means for slightly rotating the nut in the event that the pinion and engine member should abut and not mesh.
12. An engine starter including a rotatable drive shaft, a drive including a sleeve splined on the shaft, a pinion mounted on one end of said sleeve, said sleeve being adapted to be shifted longitudinally to bring the pinion into mesh with a member of the engine to be started, a nut threaded on the sleeve, a torque transmitting connection interposed between the pinion and nut, and manually operated

- mechanism for shifting the sleeve longitudinally including means for slightly rotating the nut in the event that such longitudinal shifting of the pinion is arrested.
- 5 13. An engine starter including a rotatable drive shaft, a drive including a sleeve splined on the shaft, a pinion mounted on one end of said sleeve, said sleeve being adapted to be shifted longitudinally to bring the pinion 10 into mesh with a member of the engine to be started, a nut threaded on the sleeve, a torque transmitting connection between the pinion and nut, and two manually operated longitudinally movable sleeves one of which 15 is operably connected with the first sleeve and is adapted for slight rotary movement as an incident to the stoppage of its longitudinal movement and the continued longitudinal movement of its companion sleeve.
- 20 14. An engine starter including a rotatable drive shaft, a drive including a sleeve splined on the shaft, a pinion mounted on one end of said sleeve, said sleeve being adapted to be shifted longitudinally to bring the pinion 25 into mesh with a member of the engine to be started, a nut threaded on the sleeve, a torque transmitting connection interposed between the pinion and nut, and means for slightly rotating the nut in the event that the 30 pinion and engine member should abut and not mesh, said means comprising a second sleeve operably connected with the first sleeve, and a third sleeve which is manually operable and connected with the second sleeve 35 by pin and inclined slot connection.
15. An engine starter including a rotatable drive shaft, a drive including a sleeve splined on the shaft, a pinion mounted on one end of said sleeve, said sleeve being adapted to be 40 shifted longitudinally to bring the pinion into mesh with a member of the engine to be started, a nut threaded on the sleeve, a torque transmitting connection interposed between the pinion and nut, and means for slightly 45 rotating the nut in the event that the pinion and engine member should abut and not mesh, said means comprising a second sleeve operably connected with the first sleeve, and a third sleeve which is manually operable and 50 connected with the second sleeve by pin and inclined slot connection, and a spring for holding the second and third sleeves in a normal relative position.
16. An engine starter including a rotatable 55 drive shaft, a drive including a sleeve splined on the shaft, a pinion mounted on one end of said sleeve, said sleeve being adapted to be shifted longitudinally to bring the pinion into mesh with a member of the engine to be 60 started, a nut threaded on the sleeve, a torque transmitting connection interposed between the pinion and nut, and means for slightly 65 rotating the nut in the event that the pinion and engine member should abut and not mesh, said means comprising a second sleeve oper-

ably connected with the first sleeve, and a third sleeve which is manually operable and connected with the second sleeve by pin and inclined slot connection, said pin being carried by the third sleeve and the slot being in 70 the second sleeve, a spring retainer connected with the second sleeve, a thimble connected with said pin, and a spring arranged between said retainer and thimble to hold the second and third sleeves in a normal relative position. 75

17. An engine starter including a rotatable drive shaft, a drive including a sleeve splined on the shaft, a pinion mounted on one end of said sleeve, said sleeve being adapted to be shifted longitudinally to bring the pinion 80 into mesh with a member of the engine to be started, a nut threaded on the sleeve, a torque transmitting connection interposed between the pinion and nut, and means for slightly 85 rotating the nut in the event that the pinion and engine member should abut and not mesh, said means comprising a second sleeve operably connected with the first sleeve, and a third sleeve which is manually operable and connected with the second sleeve by pin and inclined slot connection, said nut being in the path of longitudinal movement of the second sleeve and adapted to be engaged and partially rotated by the latter. 90

18. An engine starter including a rotatable drive shaft, a drive including a sleeve splined on the shaft, a pinion mounted on one end of said sleeve, said sleeve being adapted to be shifted longitudinally to bring the pinion 100 into mesh with a member of the engine to be started, a nut threaded on the sleeve, a torque transmitting connection interposed between the pinion and nut, and means for slightly 105 rotating the nut in the event that the pinion and engine member should abut and not mesh, said means comprising a second sleeve operably connected with the first sleeve, and a third sleeve which is manually operable and connected with the second sleeve by 110 pin and inclined slot connection, said nut being in the path of longitudinal movement of the second sleeve, the adjacent faces of the nut and second sleeve having teeth.

19. An engine starter including a rotatable 115 drive shaft, and a drive mounted thereon and driven thereby including a sleeve mounted on the shaft for longitudinal movement thereof and rotary movement therewith, a driving member carried by said sleeve and adapted to be shifted longitudinally to engage a member of the engine to be started, a control member mounted on the sleeve for longitudinal movement thereof and rotary movement therewith, a torque transmitting connection 120 interposed between the driving member and the control member, and means comprising a second sleeve operably connected with the first sleeve, a manually operated third sleeve slideable on said shaft and having pin and inclined 125

130

slot connection with the second sleeve and having pin and straight slot connection with the first sleeve, whereby the second is slightly rotated by the stoppage of longitudinal movement of the driving member and the continued longitudinal movement of the third sleeve and the first sleeve is held from

rotation during this time, and yielding means for holding the second and third sleeves in a normal relative position.

In testimony whereof, I have subscribed my name.

WILLIAM L. McGRATH.
